UNITED STATES PATENT OFFICE.

EARL E. BERRY, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

SAND-SETTLING BOX.

1,407,919.

Specification of Letters Patent. Patented Feb. 28, 1922.

Application filed March 29, 1919. Serial No. 286,069.

To all whom it may concern:

Be it known that I, EARL E. BERRY, a citizen of the United States, residing at Kennett Square, county of Chester, and State of

5 Pennsylvania, have invented a new and useful Improvement in Sand-Settling Boxes, of which the following is a full, clear, and exact description, reference being had to the accompanying drawings, which form a part

10 of this specification.

The object of my invention is to provide a sand settling box of such construction that it may be adjusted to effect the separation of all the sand from the water or the separation 15 of sand of any degree of coarseness from the finer sand and the water, or so that a plurality of such sand boxes may be arranged to effect the separation of the sand into different grades of fineness.

20 A preferred embodiment of the invention is shown in the accompanying drawings, in which—

Fig. 1 is a long, sectional view, somewhat diagrammatic.

25 Fig. 2 is a detail face view of the water discharge end of the settling tank.

Fig. 3 is a detail side view of this end of the tank partly broken away.

The settling tank *a* is of known form, 30 comprising a wooden box which is higher at one end than at the other. Near opposite ends of the tank turn two sprocket wheels *b* and *c*, the lower one being driven from power driven mechanism not shown. An

35 endless sprocket chain *d* engages both sprocket wheels, the upper reach of the chain being maintained from sagging by idle sprocket wheels intermediate the wheels *b* and *c*. The sprocket chain is driven in the

40 direction of the arrow and is provided, on its outer face, with flights *e*. The chain is of such length that a part of the reach thereof traveling from the lower driving sprocket to the upper driven sprocket is more or less

45 close to the bottom of the tank so that the flights will, during the travel of the chain, drag part way along the bottom of the tank and bank the sand toward the higher end of the tank and convey it up the incline *g* and discharge it. The upper sprocket wheel *c* is mounted to turn in a bearing *h* which, as shown, is adjustable toward and from the other sprocket wheel to regulate the degree

50 of sag of the chain. The bearing *h* as well

as the other bearings for the various sprocket 55 wheels are so mounted that all portions of all of said wheels are above the highest water level in the tank.

The lower end of the tank is provided with an adjustable gate and a discharge spout 60 carried thereby, the latter maintaining the water in the tank at the level of the bottom of the end of the spout communicating with the tank. This arrangement is a novel one performing new and useful functions and 65 will be particularly described; it being understood, however, that the structural details may be varied without departing from the invention.

At the lower end of the tank, upright and 70 cross beams are arranged to form a rectangular frame-work or gate-way *i*, to which is bolted, at opposite sides, vertical angle bars *j*. Secured to the outwardly projecting wings of the bars *j* are angle bars *k* of 75 smaller cross section. Between the gate frame and the lateral wings of the angle bars *k* are formed vertically extending grooves or ways within which the vertical edges of the gate *m* are slidable. 80

The gate *m* is cut down in height, throughout the generator part of its width, to form an overflow mouth for the escape of water (or water and sand) from the box, a discharge spout *n* being so secured to the 85 gate as to communicate with this cut-away portion.

The gate *m* has secured to its outer face two vertically extending racks *o* which are in engagement with two pinions *p* on a cross-shaft *q* outside the bottom of the tank. The shaft *q* carries a worm-wheel *r*, which is driven from a worm *s* on an upright shaft *t*, the latter being equipped, at its upper end, with a hand wheel *u*. Thereby the gate *m* 95 may be raised or lowered.

The gate *m* should be secured tightly in the position to which it is adjusted. Ears *v* are secured at intervals to the upright angle bars *j* and bolts *w* extend through these ears 100 and are turned to tightly abut against the gate adjacent to its edges. The laterally extending wings of the angle bars *k* are notched at intervals to permit the bolts *w* to pass through them and directly engage 105 the gate. Extending transversely outside the bottom part of the box is an angle bar *x* having lugs *y* secured to the inner face

thereof and bolts z are screw-threaded through this wing and these lugs and engage the gate adjacent to its lower edge.

It will be understood, therefore, that, preparatory to adjusting the vertical position of the gate, the bolts w and z are loosened, the hand-wheel u is turned to adjust the gate, and then the bolts w and z are re-tightened, the gate being thereby pressed 10 against the gate frame so as to afford a substantially water-tight joint.

In operation, the mixture of water and sand will be fed into the open top of the tank by any suitable pipe conveyance. The 15 sand, by reason of its higher specific gravity, will tend to settle to the bottom, while the water and loam discharge through the overflow spout n .

If the adjustable overflow gate is in a 20 relatively high position, the volume of water in the tank is so great that the velocity of the water is relatively low, giving all the sand ample time to sink, so that little, if any, sand will escape with the water. 25 When the gate is in a relatively low position, the velocity of the water will be relatively great and the fine sand will be largely carried off with the outflowing water, leaving only the coarse sand to be carried out by 30 the moving flights. It will be appreciated that by arranging the sand settling boxes in batteries, and feeding the mixture of water and sand successively through a series (two or more) of boxes, the sand may be 35 separated into different grades, and that the

positions of the gates may be so adjusted as to secure any size sand that may be wanted.

Having now fully described my invention, what I claim and desire to protect by Letters 40 Patent is:

A sand settling and washing apparatus comprising a relatively long box closed at one end, a sand discharge chute at the closed end leading upwardly and outwardly, an 45 adjustable overflow chute leading from the other end through which the water and lighter materials pass, the upper end of the sand discharge being above the highest water level which can be maintained in the tank, a 50 portion of the bottom of the tank being substantially in a horizontal plane, an endless chain conveyor, sprocket wheels for said chain above the water line, outwardly extending spaced flights on the chain, means 55 between the sprocket wheels for preventing the upper reach of sprocket chain from sagging to throw all the slack in the lower reach, said chain having sufficient slack to permit the end edges of the flights to be 60 dragged along a portion of the bottom of the box, while one of the sprocket wheels is so positioned that the end edges of the flights are dragged along the bottom of the discharge chute as they pass from the box. 65

In testimony of which invention, I have hereunto set my hand, at Kennett Square, Pa. on this 27th day of March, 1919.

EARL E. BERRY.
